Primary Examiner—B. J. Bullock

Attorney, Agent, or Firm—Dunlap, Codding & Peterson

CLAIM

The ornamental design for a flower pot cover, substantially as shown and described.

DESCRIPTION

FIG. 1 is a top plan view of the flower pot cover showing our new design, the textured pattern on the inner surface is partially shown and is understood to repeat across the entire surface.

FIG. 2 is a front elevational view thereof.

FIG. 3 is a rear elevational view thereof.

FIG. 4 is a side elevational view thereof.

FIG. 5 is a side elevational view similar to FIG. 4, but showing the side opposite that shown in FIG. 4.

FIG. 6 is a bottom plan view thereof which partially shows the basketweave pattern on the outer surface and is understood to repeat across the entire surface.

FIG. 7 is an enlarged plan view of the basketweave pattern shown in FIG. 6.

The flower pot cover has no substantial thickness.
